RECORD MAGAZINE FOR AUTOMATIC
PHONOGRAFSPaul U. Lannerd, Fort Wayne, Ind., assignor to
The Capehart Corporation, Fort Wayne, Ind.

Application August 30, 1930, Serial No. 478,861

4 Claims. (Cl. 274—10)

This invention relates to an automatic record changing phonograph and more particularly the mechanism for placing and removing a record upon the turntable thereof.

5 The object of the invention is to provide a magazine for containing a plurality of records, of simple construction which may either be mounted in fixed position with respect to the turntable or movable with respect thereto. The magazine 10 is adapted to release a record to drop into playing position upon the turntable.

Another feature of the invention resides in the means for releasing a record by a simple reciprocal movement and particularly permitting the record to drop one edge at a time so as 15 to prevent breakage.

Another feature of the invention resides in the arrangement whereby the magazine may be rotated or inverted with respect to the turntable 20 so as to deposit a record thereon from one side of the stack of records contained therein, and pick up said record from the turntable adjacent the other side of the stack of records and thereon be reversed to deposit a new record from the 25 first mentioned side.

The full nature of the invention will be understood from the accompanying drawings and the following description and claims:

Fig. 1 is a side elevation of the mechanism 30 showing portions thereof in cross section with the magazine in elevated position for permitting record playing shown in full lines, and in lowered position for record changing shown in dotted lines. Fig. 2 is a plan view of the record changing magazine. Fig. 3 is a central vertical section taken therethrough showing a record supported therein. Fig. 4 is the same as Fig. 3 showing a record with one side thereof released. Fig. 5 is the same as Fig. 4 showing the record 40 completely released from the magazine. Fig. 6 is a modified form showing the magazine mounted in fixed position relative to the turntable.

In the drawings there is shown a machine having a supporting frame 10 mounted upon the side frame 11. Rotatably mounted upon the supporting frame 10 there is a turntable 12 driven by a suitable motor contained in the motor housing 13 suspended from below the turntable. The turntable is driven through the spindle 14 which 50 protrudes upwardly beyond the upper surface of the turntable to provide a centering pin for a record.

The record changing magazine comprises an annular ring 15 of an inside diameter sufficient 55 to contain a plurality of records 16. On one side

thereof there is a false bottom 17 and a bottom ring 18 spaced therefrom substantially the thickness of one record and secured to the false bottom by the screws 19. Said ring 18 is provided with inwardly protruding lip portions 20 and 21, best shown in Figure 2, said ring and lip portions being fixed relative to the magazine. Slidably mounted between the bottom ring 18 and the false bottom 17 there is a discharge ring 22 having an elongated slotted projection 23 60 on one side thereof and a similar projection 24 on the other side thereof. Intermediate thereof, there are provided elongated slots 25 through which the pins 26 extend for guiding the sliding ring in the magazine. On one side of the ring, 65 and adjacent the projection 24 there is an inwardly projecting record supporting seat 27 conforming when in advanced position to the inwardly projecting lip 21.

In operation, a stack of records 16 are normally 75 supported in the magazine by the lip 20 of the fixed bottom ring, on one side of the record, and by the seat 27 of the sliding ring 22 on the other side of the record. When it is desired to transfer a record from the magazine to the turntable, the 80 sliding ring is moved to the right as indicated by the arrow in Figure 4 so that the bottom record of the stack contained in the magazine is dropped by the seat 27 onto the lip 21 and is 85 pushed inwardly between the false bottom of the magazine and the bottom ring by the forward movement of the sliding ring 22 above the lip 20. In that position the left hand edge of the record is caused to drop off of the lip 20, while the right hand side is held in suspended position between the false bottom 17 and the lip 21. Thus, in this 90 position the record hangs at an angle as illustrated in Figure 4 with the center hole 30 thereof to the right of the centering pin 31 of the turntable. The sliding ring is then moved to the left as indicated by the arrow in Figure 5 so that the record is pushed from between the lip 21 and the false bottom 17 by the seat 27. The center 95 hole of the record is then directly over the centering pin and the record is free to drop down thereon.

From the above described construction, it will be noted that the records are "shuffled" from the bottom of the stack, first one side being released and then the other. This is accomplished by the 105 reciprocating action of the sliding ring.

Various applications of the magazine may be employed, one being illustrated herein in connection with the mechanism shown in Figure 1 and 110

another in connection with the modified mechanism shown in Figure 6.

Various means of reciprocating the sliding ring may be employed, two of which are illustrated 5 herein.

- In Figure 1 the magazine is pivotally mounted between the oscillating arms 32 and on each side thereof adjacent its axis of rotation there are pins 33 and 34. The arms 32 are pivotally mounted at 35 on the support 10 and through suitable connections are caused to lower the magazine into position shown in dotted lines immediately over the turntable. Thereupon, a record is released onto the turntable as above described. 10
- Upon the record being released the arms 32 swing upwardly to carry the magazine into raised position. Simultaneously, the arm 36 has engaged the pin 34 by the head 37 and caused the magazine to rotate one-half revolution. 15
- After the record has been played, the magazine is brought into position over the turntable with the other side thereof adjacent thereto. From that side of the magazine, as illustrated in Fig. 1, a plurality of spring actuated latches 38 extend at spaced intervals about the periphery. As the magazine approaches the record on the turntable, the latches 38 by reason of their bevelled faces, slip over the edge of the record until the record that was on the turntable lies adjacent the lowest record in the magazine. The latches then snap under the record so as to support it with the rest of the records in the magazine while the magazine is again elevated and reversed to the position shown in full lines in Fig. 1. The reversing of the record during the upward movement is caused by the head 37 engaging the pin 33 so that the upward swing of the arm 32, coupled with the action of the arm 36, causes the magazine to turn one-half revolution to bring the latches 38 from their downwardly extending position to the upwardly extending position as shown. In this position, when the magazine is again lowered, a new record will be deposited on the turntable. The particular details of the latches 38 and the above described mechanism, which forms no part of this invention, is more specifically shown and described in the co-pending application of Paul F. Wilber, Serial No. 213,268, filed Aug. 16, 1927 for Phonograph record transfer mechanism. 25

The record actuating mechanism is driven through the bevelled pinions 39 from the turntable motor or any other suitable driving means, the driven pinion 39 driving the gear 40 which, in turn, drives the gear 41 on the shaft 42. The shaft 42 drives the pinion 43 which, in turn, drives the gear 44 in which there is eccentrically mounted the crank pin 45. Said crank pin is connected by a universal joint with the connecting rod 46 having its other end connected with the arms 32 so as to raise and lower said arms about their pivotal mounting 35. Directly connected with said arms there is a lever 47 pivotally connected with the link 48 connecting one end of the lever 49 which lever is connected with the other end of the arm 36 and pivotally mounted upon one of the arms 32 as also more specifically shown and described in the above mentioned co-pending application of Paul F. Wilber. 30

The reciprocating action of the sliding ring 22 is obtained through the medium of the fixed cam surface 50 mounted upon the support 10. The projection 24 of said ring has an arm 51 pivotally connected thereto at 52 in such man-

ner as to swing downwardly on the pivot but held against upward movement. Upon the magazine being brought into discharge position above the turntable, a roller 53 engages the cam surface 50 and pulls the sliding ring toward the right in the direction of the arrow as shown in Figure 4 for releasing the left hand edge of the record. Upon the roller 53 riding off of the cam surface 50, the spring 54 connecting the end of the arm 51 with the magazine causes it to move in the opposite direction as indicated by the arrow in Figure 5 for releasing the other side of the record and permitting it to drop onto the turntable. 35

In the modified form shown in Figure 6, the magazine 15 is fixedly mounted above the turntable 12 upon the standards 60. The projection 24 of the sliding ring is connected to a crank 61 actuated by the shaft 62 and driven from any suitable source, being more particularly shown and described in the co-pending application of Collison, Serial No. 477,218, filed Aug. 23, 1930 for Automatic phonograph. By this means the reciprocating action of the sliding ring is obtained for releasing the record as above described so that it drops over the upwardly extending centering pin 114. 90

The invention claimed is:

1. In an automatic phonograph, a magazine for holding a plurality of sound reproducing disks in stacked relation to be discharged onto a turntable in reproducing position, comprising a body portion, supporting means secured to said body portion and spaced therefrom having an outwardly projecting portion for temporarily supporting the opposite marginal edges of the bottom disk thereon, and a member slidably mounted between said supporting means and body portion for releasing first one side of the disk and then the other therefrom. 105

2. In an automatic phonograph, a magazine for holding a plurality of sound reproducing disks in stacked relation to be discharged onto a turntable in reproducing position comprising a body portion, a ring rigidly secured thereto for temporarily supporting opposite marginal edges of the bottom disk, and an annular member slidably mounted between said ring and body portion adapted to push one edge of said disk off of said ring when moved in one direction and the other edge therefrom when moved in the reverse direction. 115

3. In an automatic phonograph, a magazine for holding a plurality of sound reproducing disks in stacked relation to be discharged onto a turntable in reproducing position, comprising a body portion, a ring secured thereto for supporting the opposite marginal edges of the bottom disk, said ring being spaced from the body portion substantially the thickness of a disk, and a sliding member adapted to push one edge of the disk off of said ring while said ring retains the other edge thereof and thereafter push said last mentioned edge from the ring when moved in the reverse direction, whereby said disk will be discharged 130 from the magazine. 135

4. In an automatic phonograph, a magazine for holding a plurality of sound reproducing disks in stacked relation to be discharged onto a turntable in reproducing position, comprising a body portion, a seating means secured thereto and spaced therefrom substantially the thickness of a disk, said seating means being provided with inwardly projecting lips on opposite sides thereof for supporting the opposite marginal edges of the 145 150

1,965,744

bottom disk, and a sliding ring mounted between said seating means and body portion adapted to temporarily support one edge of the bottom disk above one of said lips, whereby upon said sliding ring being moved in one direction it will force the other edge of the record off of its corresponding lip while causing the first mentioned opposite

edge thereof to be gripped between the adjacent lip and body portion, and when moved in the opposite direction will push the gripped edge of the disk out of engagement with the adjacent lip so as to completely release it from the magazine. 80
